Primary Examiner — Mark A Goodwin

(57) **CLAIM**

The ornamental design for an agricultural machine as shown and described.

DESCRIPTION

1. Agricultural machine

Design 1, as is shown in figures 1.1 to 1.9, is based on an agricultural machine of the type of bale bundler.

Fig. 1.1 is a top left perspective view of an agricultural machine showing my new design.

Fig. 1.2 is a left side view thereof.

Fig. 1.3 is a right side view thereof.

Fig. 1.4 is a front view thereof.

Fig. 1.5 is a rear view thereof.

Fig. 1.6 is a top left rear perspective view thereof.

Fig. 1.7 is a top left rear perspective view thereof shown in an open configuration.

Fig. 1.8 is a left side view thereof shown in an open configuration.

Fig. 1.9 is a top right rear perspective view thereof.

1 Claim, 9 Drawing Sheets(56)
